UNITED STATES PATENT OFFICE.

JONAS ALBERT JOHNSEN, OF COPENHAGEN, DENMARK.

APPARATUS FOR PRODUCING AND UTILIZING MICRO MOVEMENTS IN WEAK-CURRENT TECHNICS.

1,075,786.

Specification of Letters Patent Patented Oct. 14, 1913.

Application filed April 11, 1911. Serial No. 620,267.

To all whom it may concern:

Be it known that I, JONAS ALBERT JOHNSEN, of No. 20 Læsøegade, Copenhagen, in the Kingdom of Denmark, mechanical engineer, and a subject of the King of Norway, have invented certain new and useful Improvements in Apparatus for Producing and Utilizing Micro Movements in Weak-Current Technics; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Experiments heretofore carried out to cause a coil, wound armature or other conductor arranged in a magnetic field supplied with local current to effect movements of such relative magnitude, strength and precision to long distances under the influence of weak current impulses (such for example as telegraph or telephone currents) as to render it possible, (for example in employing a microphone inserted in a local circuit) to send a corresponding but stronger communication current along a long line have led to no practical results. Neither has it been possible (for example by connecting the said conductors with a membrane) to obtain a perfectly clear reproduction of the communication or by stronger current impulses to obtain a louder reproduction. On the other hand it has not been found possible by direct transmission of the micro movements to the said conductor (for example by means of a membrane which is spoken onto) to produce induced currents of substantially greater magnitude than ordinary telephone currents for example. The consideration of the possibilities of a practical solution of these problems has led to the conclusion that with apparatus of the said kind which consists of an electro-magnet with a suitable field, a source of current for feeding the same, a conductor movably arranged in the field and connected with a line from which the conductor can either

receive current impulses or to which it can give current impulses, and finally of a member mechanically connected with the movable conductor and either displaced by it or displacing it (in the former case for producing a relay effect in a local microphone circuit for example or for direct reproduction of a conversation, in the latter case for the purpose of being influenced by speech vibrations or the like) which as regards the two last-named elements and the elements connected therewith has already been largely done probably in utilizing the practical possibilities for ready displacability and ease of action and so forth. The only means remaining by which any considerable increase of effect can be obtained therefore resides in the improvement of the two first-named elements. It is certainly surprising that earlier inventors have contented themselves in this field of research not only with electro-magnets, which, as regards the number of the ampere windings and the lines of force come far below the limits of practical possibilities but—even with simple steel magnets, although in accordance with a known electro-physical law the mechanical forces to which a conductor traversed by current is subjected in a magnetic field are proportionate to the strength of the field. On the other hand, it must be assumed that the strengths of the field heretofore utilized, even when the lines of force could only be counted by hundreds, were more than ample for producing the micro effect here in question and that an increase in the strength of field, which in the case of weak magnets is already carried far beyond the magnitude of the mechanical equivalents of this micro effect, would either be of no importance or would even reduce the effect. Nevertheless experiments in this connection have demonstrated that the micro effect is increased or rather is made practically efficient by increasing the strength of the field and that by increasing the strength of the field to the limit of practical possibilities effects of unexpected strength and purity are produced. This is only explainable by the extremely small efficiency that has latterly been shown

to prevail with telephones and the like apparatus. The present method consequently resides in the fact that in producing or utilizing acoustic and similar micro movements of a conductor carrying a weak current in a magnetic field, such a magnetic super-saturation and strength of this field is employed that a minimum flux of about 20000 lines of force per square cm. or a 10 number of lines of force amounting to hundreds of thousands or even millions concentrated on the weak current conductor are obtained.

An annular field and the uniform distribution of lines of force running perpendicularly to the windings of a coil axially displaceable in the annular field are already known in connection with weak current relays and no protection is applied for on 20 this point generally, but in this connection the invention extends only to the employment of such devices in conjunction with strong current magnets, the poles of which are arranged for concentration of the lines 25 of force. Having regard to the greater amplitudes or oscillations of a weak current conductor rendered possible by the invention it is advantageous to employ for its suspension and that of the other elements (micro- 30 phone and the like) connected therewith a special resilient suspension member which permits of producing these large oscillations even at high periodicities (over-tones) and without producing acoustic effects by reason 35 of their inertia. The membranes heretofore generally employed for similar purposes and analogous resilient supporting devices held at their outer periphery and connected at the center with the oscillating member present a 40 large useless mass or area, by which acoustic effects due to their inertia are produced, and before all impede the transmission of the over tones which are essential for clearness in the conversation. Relatively thereto the 45 present suspension member is mainly characterized by the fact that it is held at the center or the middle points by relatively narrow springs or resilient arms while the weak current conductor and the other oscillating members are connected with its outer 50 ends. An apparatus capable of operating in accordance with this principle is broadly characterized by the fact that between the poles of a strong current magnet or strong 55 current compound magnet a field (preferably closed) with high concentration and as far as possible uniform distribution of the lines of force is interposed, these lines of force running as far as possible perpendicularly 60 to the windings of a weak current coil axially displaceable in the field and resiliently held in its position of equilibrium, the said coil being magnetically energized or not.

In the accompanying drawing: Figures 1 65 to 3 illustrate different constructional forms

of a strong current magnet with highly concentrated field in which the weak current coil is axially displaceable (for the sake of clearness this coil is omitted in Fig. 3). Fig. 4 is a top view of the compound magnet shown in Fig. 3. Fig. 5 illustrates the connection of a weak current coil with a local microphone circuit. Fig. 6 shows the combination of a weak current coil with an air action member to a larger scale. Figs. 7 to 75 70 75 80 85 90 95 100 105 110 115 120 125 130

The forms of magnet illustrated present nothing special *per se* if the strong current electro-magnets utilized in experimental physics are compared therewith. This applies more particularly to the form illustrated in Fig. 1 with simple pole cones 1 and 2 directed toward each other. The novelty of the apparatus resides in the fact that the enormous number of lines of force (mainly arc-shaped) proceeding from the pole cones, that is to say, from their points act at favorable angles on a coil 3 displaceable axially, that is to say, from one pole to the other of double conical formation and inserted in the weak current line 4, 5, a telegraph or telephone line for example. The number of the ampere windings on the magnet coils 6 and 7 may be from 2000 to 20000. The current can be taken from an ordinary town main or from a lamp socket or it may be produced by a special source of current 8.

In the drawing the coils stop at the foot of the base of the cone; in practice it is, however, preferable to allow them to extend almost to the apex of the cone, that is to say, to the limit of the field with which it is desired to operate.

Fig. 2 illustrates the magnet cores surrounded by a magnetizing coil 6^a common to them all. The pole 2^a is in the form of a hollow cone inclosing the pole point 1^a in such a manner that a concentrated and relatively very small field of conical annular form is produced in which the correspondingly small conical weak current coil 3^a is displaceable axially. Behind the hollow cone a chamber 9 is provided for the reception of the apparatus (a microphone for example) with which the coil 3^a is to be connected. In order that the magnetic field may remain accessible one of the cores such as the core 2^a, can be arranged in such a manner that it can be removed through the lateral part 10 or together with it.

While the fields illustrated in Figs. 1 and 2 are uniform that is to say, they theoretically present the same magnetic intensity at every point located at the same radial distance in a plane perpendicular to the axis of the field the field shown in Figs. 3 and 4 is

open at different places. This field is formed between the pole cone 1^b and two or more pole points 2^b arranged perpendicularly or obliquely to its axis of mutually like but opposite polarity to the pole 1^b (see the winding diagram Fig. 3). The points can also run obliquely to the axis of the field of the magnets 6^b and 7^b and assume an oblique position in which the longitudinal axis of the points and of the corresponding iron cores are perpendicular and their pole faces parallel from the front to the generating lines of the cone 1^b. In accordance with Fig. 3 the points 2^b are provided with recesses or notches 11 the pole faces of which run parallel with the pole face 1^b. On the upper side they can be provided with wider recesses 12 which serve to prevent dispersion of the lines of force. In the field a coil 3^a (Fig. 2) can be arranged. However, when using three, four or more pole points 2^b a coil of pyramidal form with a triangular, quadrangular or other polygonal base can be used, the pole point 1^b being made of corresponding pyramidal form.

The magnet shown in section in Fig. 5 is either an entirely closed bell or iron inclosed magnet or provided with an open frame as shown in Figs. 3 and 4 only the coils 7^b being omitted and their cores united to form a single part 13. Preferably the magnet comprises a central opening the form of which corresponds to that of the pole point 1^c of the magnet 6^c or else (Fig. 5) a larger opening in which a special annular pole piece 2^c is arranged. The weak current coil 3^c interposed on the line 4^c, 5^c is connected with a rod or spatula-shaped member 15 for example by means of insulated arms 14, this member 15 being inclosed in a receptacle 16 containing granular carbon. This microphone 15, 16 is connected up with the primary winding 17 of an induction apparatus in a local circuit 18. A line wire 20, 21 can proceed from the secondary winding 19. Fig. 5 therefore represents an embodiment for the employment of the invention as a weak current relay. It will be noted that the coil 3^c inserted in the magnet field in such a manner as to be axially displaceable in a suitably resilient manner is acted upon under the influence of the current impulses coming from the line 4^c, 5^c toward one or other of the poles away from its position of equilibrium. The spatula-shaped member 15 will participate in these micro movements. In agreement herewith the resistance constituted by the carbon bodies or the like between the member 15 and the conducting wall 22 of the receptacle 16 and also the strength of current in the induction apparatus 17, 19 and the line 20, 21 is modified. Any other suitable form of microphone can be employed in place of that here illustrated.

The microphone 15, 16 illustrated could be

formed in duplicate by arranging the other wall 22^a of the receptacle 16 as a conductor and inserting it in the primary circuit 17 as indicated. When on the right hand side of the microphone electrode 15 (owing to its movement toward the right hand) a diminution of the resistance and therefore an increase in the strength of the current in the branch line 18 takes place, simultaneously on the left hand of the microphone electrode an increase in the resistance and therefore a weakening of the current in the branch line 18^a will take place. By suitably connecting the secondary coils 19 and 19^a in series or in parallel both actions are rendered cumulative.

In Fig. 6 the coil 3^d is connected with a membrane or a plate 23 which causes the air to vibrate directly as in a telephone receiver, or which, inversely, is displaced by the vibrations of the air and is thus able to displace the coil 3^d whereby a current such as an acoustic operated current for example is induced in the line 4^d, 5^d. 24 is a sound horn and 25 a casing surrounding the plate 23 in which the latter is freely displaceable, somewhat in the manner of a piston. 26 are rods connecting the coil 3^d with the plate 23.

In order to avoid dispersion of the lines of force, that is to say in order to obtain the maximum concentration of the lines of force in the field, a cone-shaped recess 12 is provided externally upon the pole piece 2^d, and corresponds to the recess shown in Figs. 3 and 4, while the inner side is provided with a conical face 30. The pole face proper 1^d of the other pole protrudes somewhat in front of the annular cone 31 arranged between it and the thicker core. The material is also removed from the center of the point so that a conical or hemispherical recess 32 is formed. The magnetizing coil must extend almost to the head 1^d. In particular, generally speaking in all these apparatus the magnet frame must be wound as far as possible and the iron cores made as long as possible. In order to avoid Foucault or eddy currents in the poles they are preferably recessed so as to interrupt the continuity of conduction on their outer stratum.

Fig. 6 illustrates by way of example a spherical field. With this object the coil 3^d presents the form of a hemispherical shell. A coil of this kind can be formed by employing suitable cement or binding material and winding a very fine, insulated aluminium, copper or silver wire on a mandrel semi-circular in cross section in single or multiple layers, and eventually inserting magnetic elements between the layers. The ends of the coil can be reinforced by means of small metal clamps 33 or the like (Fig. 7). As an example of the arrangement of the coil 3^d in the field a plate 27 is shown in Fig. 6; it is arranged in the pole piece 2^d and con-

nected by a rod 28 with another plate 29 secured to the coil. The plates 27 and 29 or one of them are made resilient or formed as suspension members in the manner indicated above. The rods 26 pass freely through the plate 27. If desired the plate 28 can be omitted, in which case its purpose is served by the membrane 27 which is fixed at its periphery or at the ends. In this case the rods 26 are also dispensed with or their outer ends are connected with the plate 27 and the rod 28 and the plate 29 are omitted.

In accordance with Fig. 7 the coil is provided with a resilient supporting part or plate 29, which can be secured to the pole 1^a or 1^c (Figs. 2 and 5) by means of screws 34 and 35 for example. The windings of such a coil run in the manner of the convolutions of a conical screw. A receptacle 16 containing granular carbon can be connected with one end of the suspension member 29 which in this figure lies horizontally, in such a manner that during the movements of the coil 3^e the grains of carbon are displaced with it. In this case the other pole 15 of the microphone is secured in some appropriate manner.

Figs. 8 and 9 illustrate a cylindrical coil, which is employed when the faces of the pole pieces, which are directed toward the field and also toward each other, are cylindrical, the coil 3^e being made cylindrical to correspond. The resilient suspension member 29 is provided in this figure at each end with a microphone electrode 15 each of them working in its granular carbon receptacle 16. The two microphones can be connected in series or parallel in suitable local circuits such as 17, 18 (Fig. 5). The freely resilient arms 36 of the suspension member 29 held at the middle, are connected with the coil by means of laterally bent projections 37, lugs, bolted rods or the like.

Fig. 10 shows a spring provided with very long arms 36 and Fig. 11 a spring with three arms 36.

Figs. 12 and 13 show how a spring which is long in itself can be caused to oscillate with relatively short arms 36 by utilizing two or more screws 34 or the like (Fig. 12) or by employing a separate plate 38 (Fig. 13) which retains or damps the middle portion beyond a given length. A similar damping can also be produced by using a flat spring by twisting it so that its middle portion is turned on edge.

The springs or their arms 26 shown in Figs. 6-13 need not be flat; they might equally well be round or hollow or present other suitable cross sections. The arms 36 need not be connected one with the other at a common center, but each may constitute an independent spring in cases when more than one is provided, in such a manner that

tones due to inertia are avoided. These two or more springs can be secured at a common fixed point, or at a number of different fixed points.

The form of the field and of the coil can of course be modified in various ways as regards profile and cross section. They can be straight, broken or curved in profile and the cross section may be round, oval, polygonal and so forth.

What I claim and desire to secure by Letters Patent of the United States is:—

1. An apparatus for producing and utilizing acoustic and similar micro displacements of a coil carrying a weak current in a concentric magnet field, comprising a magnet field constituted by strong current electro-magnets and a coil carrying a weak current, the diameter of said coil being smaller than the diameter of the core of the concentric magnet, and said core being provided with a concentration pole which closely surrounds said coil.

2. An apparatus for rendering the movements of a conductor carrying a weak current in a magnetic field capable of practical utilization comprising the combination with an electro-magnet having conical pole pieces for concentrating the lines of force of an axially displaceable conductor carrying a weak current situated in said field and connected to the ends of springs held in place at central points and constituting a reproducing device.

3. An apparatus for rendering the movements of a conductor carrying a weak current in a magnetic field capable of practical utilization comprising the combination with an electro-magnet having concave and convex cone shaped pole pieces in proximity to each other of a resiliently retained conductor carrying a weak current axially displaceable in the concentrated field induced by the said magnet poles and connected through intermediate members with a microphone.

4. An apparatus for producing and utilizing acoustic and similar micro displacements of a coil carrying a weak current in a concentric magnet field, comprising a relatively small coil and a field constituted by means of large strong current electro-magnets provided with concentration poles, and a resilient bar secured in the axis of said poles and extending transversely over said concentrated field, said coil being suspended from said bar as a freely movable body in said field.

5. An apparatus for producing and utilizing acoustic and similar micro displacements of a coil carrying a weak current in a concentric magnet field, comprising a relatively small coil and a field constituted by means of large strong current electro-magnets provided with concentration poles,

a resilient bar secured in the axis of said poles and extending transversely over said concentrated field, said coil being suspended from said bar as a freely movable body in 5 said field, and a microphone electrode also suspended from said bar as a freely movable body.

In testimony that I claim the foregoing as my invention, I have signed my name in presence of two subscribing witnesses.

JONAS ALBERT JOHNSEN.
